US0D1071208S

(12) **United States Design Patent** (10) **Patent No.:** **US D1,071,208 S**
(45) **Date of Patent:** **** Apr. 15, 2025**

(54) **GUIDE EXTENSION CATHETER**

(71) Applicant: **Cardiovascular Systems, Inc.**, St. Paul, MN (US)

(72) Inventors: **Bruce H. Asmus**, Minnetonka, MN (US); **Jared W. Connelly**, Minneapolis, MN (US)

(73) Assignee: **Cardiovascular Systems, Inc.**, St. Paul, MN (US)

(**) Term: **15 Years**

(21) Appl. No.: **29/864,986**

(22) Filed: **Jun. 30, 2022**

(57) **CLAIM**

The ornamental design for a guide extension catheter as shown and described.

DESCRIPTION

FIG. 1 is a perspective view of a guide extension catheter showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 5 Drawing Sheets
